UNITED STATES PATENT OFFICE.

HARVEY E. STONGE, OF TORONTO, ONTARIO, CANADA, ASSIGNOR TO GERALD DECOURCY O'GRADY, OF TORONTO, ONTARIO, CANADA.

NECKTIE-FORM.

1,386,140.

Specification of Letters Patent.

Patented Aug. 2, 1921.

Application filed June 2, 1921. Serial No. 474,557.

To all whom it may concern:

Be it known that I, HARVEY E. STONGE, a subject of the King of Great Britain, and a resident of the city of Toronto, in the county of York, Province of Ontario, Canada, have invented certain new and useful Improvements in Necktie-Forms, of which the following is a specification.

This invention relates to devices on which 10 a tie can be made up and by means of which it can be secured in place at the opening of a turn down collar without any part of the tie being carried around the collar, and my object is to devise a form of the simplest possible construction, and therefore cheap to 15 manufacture, which is easily attached and detached, and which exposes no metal to view when the tie is in place.

I attain my object by means of the constructions hereinafter described and illustrated in the accompanying drawings in which—

Figure 1 is a front elevation of a tie provided with my form attached to a collar; 25 and

Fig. 2 is a plan view of the form used with a bow tie, the tie being indicated in dotted lines, and showing the method of attachment of the collar.

30 In the drawings like numerals of reference indicate corresponding parts in the different figures.

The form for bow ties as shown in Fig. 2 is formed of an integral piece of spring 35 metal. For convenience in describing the same, I refer to this integral piece of metal as being formed of five parts, the two outer sections 1 being of equal length. The intermediate sections 2 are also of equal length 40 and of approximately the same length as the outer sections 1. The central section 3 is preferably approximately as long as one section 1 and one section 2 combined.

The central section 3 is given a slight 45 gradual bend to suit the shape of the collar with which it is to be used.

The intermediate sections 2 are doubled back on the central section 3, while the outer sections 1 are doubled back in the opposite 50 direction on the intermediate sections 2. As in this case, the form is secured to the ends of the turned-down portion of the collar, and not to the collar button, it is important that the portions 1 lie very tightly 55 against the portions 2 in order that the ends

of the collar may be held firmly between them. I find, however, that best results are attained by having the portions 1 contact with the portions 2 at one point only, a short distance back from the ends, leaving a 60 gradually widening opening between the portions 1 and 2 from their point of contact with one another to the bend joining these two portions. I find that this special shaping assists greatly in giving the bow a 65 proper appearance.

In order that the ends of the collar may be more easily guided between the portions 1 and 2, I prefer to flare the ends 5 of the portions 1 slightly outwardly and to 70 form loops 6 at the point of connection of the portions 2 and 3, these loops being slightly inclined in the opposite direction to the flared ends 5.

The tie will be secured to the form by 75 means of stitches passing around the portions 1 close to their connection with the portions 2, and also by stitches passing through holes formed in the flared ends 5. The band 4 of the tie will also preferably 80 pass around the portion 3.

What I claim as my invention is:—

1. A tie form formed of an integral piece of spring metal bent back upon itself at each end to a point adjacent the center, and 85 then back upon itself in the opposite direction to form jaws adapted to grip the ends of a collar; said form having a slight bend at its center, the bent back portions lying upon its convex side. 90

2. A tie form constructed as set forth in claim 1 in which the ends of the piece of metal are bent slightly outwardly to form a flaring mouth for the jaws. 95

3. A tie form constructed as set forth in claim 1 in which the ends of the piece of metal are bent slightly outwardly and a loop is formed at each of the first mentioned bends and inclined slightly inwardly to form a flaring mouth for the jaws. 100

4. A tie form constructed as set forth in claim 1 in which there is a gradually widening opening between the jaws from their gripping point to their point of connection. 105

Signed at Toronto this eighteenth day of May, 1921.

HARVEY E. STONGE.
